UNITED STATES PATENT OFFICE.

RAFFAELLO LA PEGNA, OF MILAN, ITALY.

TYPEWRITER.

Application filed December 5, 1921. Serial No. 520,119.

To all whom it may concern:

Be it known that I, RAFFAELLO LA PEGNA, a subject of the King of Italy, and resident of Milan, Italy, have invented certain new and useful Improvements in Typewriters, of which the following is a specification.

The present invention relates to typewriters and has for its object a typewriter in which each desired type may be printed 10 at the same time in a number of separate printing points by the manipulation of a single key.

The typewriter according to this invention is particularly useful in connection 15 with book-keeping, in which it is often necessary to write a given numeral, figure or word in two or more columns or rows of a page.

The typewriter according to this invention comprises a frame, a carriage travelling 20 on said frame and carrying a book or a sheet of paper to be written thereon, a number of printing sets said sets being spaced from each other and comprising a number 25 of type bar actions each of which actuates a type for its printing, electric means for operating the type actuating means of the several printing sets and electric means for putting in operative conditions the selected 30 sets, and means for operating the coupled sets to obtain the impression of any desired type in all said selected sets at the same time by the manipulation of a single operating key.

A divisional application Serial No. 35 640,761 has been filed May 22, 1923, claiming the device employing mechanical actuation. On the annexed drawings is shown by way of example an embodiment of a 40 multiple typewriter according to this invention; in said figures it is assumed the typewriter to be intended to write numerals or figures, but of course any desired character or sign may be used in the keyboard.

In said drawings: Figure 1 is a fragmentary front view of a construction of typewriter with electric transmission of the actuation, the right portion of this figure being a fragmentary section made along 45 lines 1'-1', 1"-1" and 1'''-1''' respectively, of Figure 2; Figure 2 is a fragmentary plan section on lines 2'-2'; 2"-2" and 2'''-2''' respectively, of Figure 1; Figure 3 is a vertical transverse section on 50 3-3 Figure 1; Figure 4 is a vertical trans-

verse section on 4-4 of Figure 1; Figure 5 is a similar section on line 5-5 of Figure 1; Figure 6 is a horizontal section on line 6-6 of Figure 1; Figure 7 is a similar section on line 7-7 of Figure 1; Figure 8 is a diagram of the electric connections and Figure 9 is the side view of one of the actuating means for controlling the electric circuits.

In the drawings, 1 is a frame or support 60 on which are mounted a number of printing sets, each set being shown as a whole by a reference I, II, III, (Figs. 1 and 2); it is assumed that the apparatus comprises three sets but of course the number of these sets may be any desired one; said sets are hereinafter particularly described and the several levers of each set are adapted to strike the respective types at a common printing point as usual in typewriters.

Said printing sets, which may be in any 70 desired number, as above stated, are located at a desired distance from each other; each of them being in position to write on a desired point of the printing surface which may be a paper sheet, a book page or the like. Each of said printing sets may comprise a larger number of keys and types than that shown on the drawing and one of them may be a proper typewriter adapted to write 80 any desired character.

At the front of the apparatus is movably mounted a carriage 5 having rollers 4' running on rails 4 and a rack bar 6 cooperating with the usual trip pawl 7 which controls the progression of the carriage after each 90 actuation of a key. A support 8 for the book or paper sheet to be written on is mounted to move vertically in the carriage 5.

Each printing set comprises type bar 26 mounted to move endwise in the machine 95 frame 1 and each connected with a lever 24 which is fulcrumed on the stationary supports 25 (Figure 3).

Each lever 24 has its other end pivotally connected to a rod 50 which in turn is 100 pivotally connected to one end of a lever 51 fulcrumed at 52; the opposite end of this lever is pivoted to a rod 23 which is operated in the manner hereinafter described.

In the construction illustrated it has been 105 assumed that the machine comprises three sets of type bars each set having the numerals 0 to 9; in Figure 1 is illustrated the set referred to as III and the sets I and II are shown close to the set III, but it is to be 110

understood that said sets may be in any desired number and they may be spaced to any desired distance from each other.

Each rod 23 is mounted to reciprocate in supports 1' and has secured to it a bar 53 of magnetic material, and all said bars 53 of one set are arranged at the side of each other in a vertical plane. Adjacent to these bars is located a partition 54 of nonmagnetic material which has slots 54' and is carried by a carriage 57 provided with rollers 55 running on rails 56; this carriage has as many electromagnets 58'-58"-58''' as are the sets of type bars and the polar faces of each electromagnet have the same size as one of the bars 53 and are located in one of the slots 54' which are spaced apart to the same distance as are the bars 53, of the several sets, carrying the same numerals; therefore by shifting the carriage 57 the electromagnets are carried in position to operate the same desired type bar in all the sets.

A spring 59 connected with the frame 1 acts to move the carriage 57 towards its extreme right hand position. At its other end the carriage is connected with a rod 60 mounted to move through supports 61 and pivoted to a lever 62 fulcrumed at 63, the opposite end of said lever carrying an armature 64 and facing the ends of the core of an electromagnet 65.

The rod 60 is provided with a plate 66 having steps 66' . . . whose edges are spaced from each other to the same distance as two adjacent bars 53. In front of the plate 66 are located nine rods 67' . . . in such a position as each of them faces one of the steps 66' . . . ; each of said rods is mounted to reciprocate and is pivotally connected to one end of a lever 68 fulcrumed at 69 (Figure 4) and having its opposite end pivotally connected with an armature 70 facing an electromagnet 71. On the rod 60 is secured a tooth 72 (Figure 2) which in its usual position engages a hook 73 of a lever 74 which is pivoted at 75; the other end of said lever 74 provides a transverse bar 74' engaging the teeth 76 of all the several bars 67.

All the rods 67 are engaged with a plate 77 fulcrumed at 78 (Figures 2 and 6) and having a pawl 79 adapted to engage a ratchet wheel 80 keyed on the shaft 81 of an electric commutator 82 (see Figures 4-8).

The above described device is intended to operate the shifting of the types; this operation takes place by the fact that, as hereinafter described, said electromagnets 71 are inserted in the circuit of a source of current in such a manner that when one of the electromagnets 71 is energized there is also operated the rod 67 which is adapted to engage the step of the plate 66 corresponding with the type to be written, and then is

released the stop 73 which leaves the rod 60 with the carriage 57 and plate 66 to move under the action of the spring 59 until said parts are engaged by the rod 67 above referred to, while the electromagnets 58'-58"-58''' in front of the several bars 53 actuate the selected type in the several sets.

Said commutator 82 hereinafter particularly described is operated after completing the stroke of each type bar for the purpose de-energizing the electromagnet 71 and of energizing that 65 to restore the parts 60-57 in the position of the figure, with the tooth 72 engaged by the hook 73.

On the shaft 81 is also keyed a wheel 83 (Figures 4 and 7) which is engaged by a pawl 84 of a lever 85 fulcrumed at 86 and abutting against a projection 87 of the tooth 72 fastened on the rod 60.

By the combined action of the pawl 79 operated by the bar 67 and of the pawl 84 operated by the projection 87 of the rod 60, the shaft 81 of the commutator is operated through one sixth of revolution at each operation of said bars 67 and rod 60, the ratchet wheels 80 and 83 having six teeth.

In the embodiment illustrated the commutator 82 comprises a disk of insulating material and three conducting segments 110 leaving intermediate insulating portions, 93 and the wheels 80 and 83 are provided with six teeth; therefore at each step motion produced by the wheels 80 and 83 are modified the conditions of the circuit controlled by the commutator 82. This circuit includes a source of electric current B and the electromagnet 65, which is thereby alternately energized and de-energized at each step motion of the commutator 82, for the purpose hereinafter referred to.

The hook 73 normally engages the tooth 72 of the rod 60 and keeps this rod and the carriage 57 stationary against the action of the spring 59; as soon as one of the bars 67 is carried in position to engage the plate 66 by its electromagnet 71 being energized, said hook 73 is removed from the path of the tooth 72 and it is again in position to engage it on the operation being completed.

Figure 8 shows the diagram of the circuits controlling the operation of the apparatus, that is controlling the energization of the electromagnets 71, controlling the position of the carriage 57 upon the type it is desired to print, as well as the energization of the electromagnet 65 moving back said carriage, and the energization of the electromagnets 58'-58"-58''' actuating the bars 53 and the associate type bars 26 of each selected printing set.

Said circuits comprise a battery B connected by wires 111-112 to the commutator 82 and to the electromagnet 65, as above described. Said battery B is also intended to energize the electromagnets 71 and 58'-

58"—58''' (each of these electromagnets having the numeral of the type and of the printing set corresponding to it) through circuits controlled by switches 89'—89² . . . 5 89"—90 and 88^I 88^{II} hereinafter referred to. It is to be noticed that the apparatus is assumed to be provided with a duplicate series of switches 88^A and 88^B and 89^A, 89^B . . . 10 89^I—90' for the purpose of operating the machine from two distant points but as said circuits and switches are in parallel it will suffice to describe the operation of a single series of them.

By manipulating the switches 88^I—88^{II} 15 the operator may put in condition of being energized the pair of electromagnets 58"—58'" or the pair 58"—58''' or both the pairs; of course in the case of a larger number of printing sets the switches 88 may be increased in number for making possible to 20 carry any desired series of printing sets in operation.

On the contrary the switches 89 are operated by the keys of the keyboards, each of 25 them controlling two circuits that is, assuming the switch 89' to be operated, it firstly closes the circuit of the electromagnet 71' through conductors 113, contacts 114, lever 115, conductors 116—117— electromagnet 30 71' and conductor 118; thereafter the said lever 115 contacts with the contact 119 and closes the circuit; conductors 120—121—122— electromagnets 58"—58'"—58''' , conductor 123— selectors 88^I—88^{II} and conductor 124; of course the current flows through the one or more of the electromagnets 58"—58'"—58''' whose circuit has been closed at the selectors 88^I—88^{II} as shown in respect of the electromagnets 58"—58''' in 40 Figure 8. By this operation the electromagnet 71' is energized and the corresponding rod 67 is moved into the path of the plate 66 to stop the latter with the carriage 57 in its position with the electromagnets 58"—58'"—58''' in front of the bar 53 of 45 each set which controls the respective type bar 26 having the type of the numeral 1; then the electromagnets 58" and 58''' are energized to actuate said bar 53 and type bar 26 and finally is energized the electromagnet 50 65 to bring back the rod 60 with the carriage 57, this electromagnet operating against the action of the spring 59 pulling said parts with the plate 66 in engagement with the bar 67 which has been carried in operation.

As above described the switches 89 are nine in number, like the electromagnets 71, and to each switch corresponds one numeral from 1 to 9, while a simple switch 90 is 60 provided for the 0, as this figure, which corresponds to the extreme right end position of the electromagnets 58"—58'"—58''' does not require a stop nor an electromagnet 71.

65 Figure 9 shows the manipulating gear in

respect of one of the keys operating the switches 89.

The lever 16 (Figure 9) having a key 16' moves against a return spring 20, a reciprocating bar 18 having a contact piece 115 70 which bridges a pair of contacts 114'—114' to close the circuit of the electromagnet 71 while the contacts 119'—119' are bridged thereafter by the piece 115' of the lever 16. Then the circuit is closed as follows: battery B, conductor 125, contacts 114'—115—114' (this switch being closed prior to that 115'), conductor 126'— contacts 119'—115'—119', conductors 127—128, switch 88'', conducting bar 33, conductors 129—130 and 80 battery.

The bar 33 is similar in its operation to that described. The switch 88'' is illustrated as controlled by a contact bar 33 driven into closed contact position by means of a 85 key rod 41 and engaged in this position by a spring 35 against a pawl 36 which may be removed to release said bar 33 by means of a push button 36'.

The described operating device may be 90 substituted with any other approved kind of switchboard.

The several circuits may also be controlled from a distance, as disclosed and described, and therefore the parts of the typewriter 95 may be actuated from any desired point.

The operation of this embodiment of apparatus is as follows: by the manipulation of one of the switches 88^I—88^{II} or 88^A—88^B (through the key 41 and lever 33) the operator couples in parallel the circuits of the magnets 58 of the selected sets which are to be operated at the same time; in the figure the electromagnets 58"—58''' are assumed to be put in operative conditions, the switch 88^{II} being closed (Figure 8). Then when the operator desires to write a numeral, say 1, in the two columns corresponding to the sets II and III, he acts on the switch 89'. This switch firstly 100 closes the circuit comprising the electromagnet 71' and thus is produced the attraction of the armature 70' and the oscillation of the lever 68', the rod 67' being shifted and its end projecting into the path of the plate 66. This switch is shown diagrammatically by 89' in Figure 8 and comprises the contacts 115—115' shown by Figure 9, which are operated by the key lever 16.

The distance between the rod 67' which has been displaced in the above described manner and the cooperating step 66' of the plate 66 is equal to the space through which the carriage 57 must move for the 125 purpose of causing the electromagnets 58"—58'"—58''' to have their polar faces in front of the bars 53 connected with the type bars 26 having the numeral 1. As a consequence 130 of the displacement of the rod 67' the mem-

ber 74 is rocked by the action of the tooth 76, and the tooth 73 is released from that 72 of the rod 60, the carriage 57 being moved towards the right by its springs 59 5 until the plate step 66' engages the rod 67' which has been shifted.

After this operation is effected the electromagnets 58'-58"-58''' have their poles in front of the bars 53 of the sets I-II- 10 III which operate the type bars of the numeral 1.

At the same time the motion of the rod 67' has produced the oscillation of the member 77 engaged with this rod, the pawl 15 79 being thus carried in front of another tooth of the wheel 80.

During the second portion of the stroke of the switch 89' its bar 115 closes the circuit of the electromagnets 58'-58"-58''' each 20 of which, being energized, attracts the bar 53 facing it, the actuation of this bar producing the printing stroke of the bar 26 having the type 1 through the intermediate of the gear 52-51-50-24.

25 When the switch 89' is opened after the operation (say by the action of a spring acting on the tie 18) the circuit of the switches 58'-58"-58''' is firstly cut off and the rods 26 which have been actuated 30 in the several groups are carried again in their position by their respective springs; then is cut off the circuit of the electromagnets 71' previously energized, so that the lever 68' is forced by its spring 68" 35 in its normal position and the bar 67' is restored in position. During this operation the bar 67' releases the member 77 which is restored in its original position by a spring 77' (Figure 6); therefore the pawl 40 79 operates through one step the ratchet wheel 80 which drives the shaft 81 and the commutator 82, this latter being thus carried in the position by which the circuit of the electromagnet 65 is closed. Said 45 electromagnet is thus energized and attracts the armature 64; the lever 62 is rocked and the rod 60 with the carriage 57 is moved towards left hand against the spring 59. The 50 normal conditions are thus restored, that is the tooth 72 of the rod 60 is again engaged with the tooth 73 and therefore it is locked. Before the rocking of the rod 60 towards the left is completed, the projection 87 of its tooth 72 engages the lever 55 85 and oscillates it, this moving forward the ratchet wheel 83 and the commutator 82 through one step. The commutator is thus in a position in which the circuit of the electromagnet 65 is cut off, and thus 60 the armature 64 is no longer attracted and the rod 60 is now engaged only by the tooth 72; said rod 60 is thus in condition to repeat the desired operation as soon as one of the switches 89 is operated.

65 The rods 26 of each set converge towards

one and the same printing point and the paper carrying carriage is moved to a step with regard to said point at each key operation in the well known manner; the desired numerals are thus printed in succession at the side of each other in the several columns corresponding to the sets put in operation in the machine.

The described typewriter in which the actuation of the type bar is made by electromagnetic means is particularly useful owing to the fact that it relieves the operator from any effort, the operator having only to manipulate a number of switches for putting in operative conditions the desired types and for effecting the printing of the desired types.

Of course each or a number of the type sets may comprise any number of type bars other than ten, and some of the bars 26 85 may be provided with other types than that of numerals; the machine may thus be used for writing at the same time the same word or sentence on two or more points of the sheet.

90 Of course the several type sets must be located at a suitable distance from each other and each or a number of them may consist of an usual typewriter.

It is to be understood that the described 95 machine may be provided with any desired or conventional accessory device as tabulator, carriage return key and the like; it may also be associated or combined with a computing machine or with any apparatus adapted to effect and record the results 100 of additions and other computing operations.

By the described machine may be produced at the same time and in a simple 105 and easy manner writings of any kind on several columns or rows of a sheet or of a page of a book; this machine is particularly useful in book-keeping as it minimizes the labour and the errors.

110 What I claim as my invention and desire to secure by United States Letters Patent is:—

1. A typewriter, comprising, a frame, a platen carriage mounted to move on said frame, means for producing a step by step motion of said carriage, a plurality of independent sets of type bars, each set comprising types adapted to strike on the same printing point, the several sets being spaced 115 from each other to write on separate points of the platen, actuating means for the type bars in each set, means for putting into operative condition a number of said sets while leaving in inoperative condition the 120 remaining sets, and means, comprising electromagnets, for operating the actuating means of the corresponding type bar in each of the sets which is in operative condition.

2. A typewriter comprising a frame, a platen carriage mounted to move on said frame, means for producing a step by step motion of said carriage, a plurality of sets of type bars, each set comprising a series of types adapted to strike on the same printing point and the several sets being spaced from each other to write on separate points of the platen, members in each set for actuating said type bars, an electromagnet in each set adapted to operate the actuating member of either of the types of its associate set, a circuit comprising a source of current, means for selectively inserting in said circuit a number of said electromagnets, a part carrying said electromagnets, members adapted to be shifted in position preparatory to engage said part, said members being in number equal to that of the types of each set and each of them being adapted to stop said part with the electromagnets in front of the actuating members of the respective type bars in the several sets, means for moving said part and electromagnets towards said stops, a member locking said part and electromagnets against said moving means, means operated by said stopping members for releasing said locking member after one of the said stopping members has been carried in position to engage said part, electromagnets for shifting said stopping members these electromagnets being inserted in said circuit, and key operated means for selectively energizing said stop shifting electromagnets and for energizing said type actuating electromagnets, and means for restoring the parts in the normal position. 70 75 80 85 90 95 100
3. A typewriter comprising a frame, a platen carriage mounted to move on said frame, means for producing a step by step motion of said carriage, a plurality of sets of type bars, each set comprising a series of types adapted to strike on the same printing point and the several sets being spaced from each other to write on separate points of the platen, members in each set for actuating said type bars, an electromagnet for each set adapted to operate the actuating member of either of the types of its associate set, a circuit comprising a source of current, means for selectively inserting in said circuit a number of said electromagnets, a part carrying said electromagnets, members adapted to be shifted in position preparatory to engage said part, said members being in number equal to that of the types of each set and each of them being adapted to stop said part with the electromagnets in front of the actuating members of the respective type bars in the several sets, means for moving said part and electromagnets towards said stops, a member locking said part and electromagnets against said moving means, means operated by said stopping members for releasing said locking member after one of the said stopping members has been carried in position to engage said part, electromagnets for shifting said stopping members these electromagnets being inserted in said circuit, and key operated means for selectively energizing said stop shifting electromagnets and for energizing said type actuating electromagnets, and means for restoring the parts in the normal position. 105 110 115 120 125 130
5. A typewriter comprising a frame, a platen carriage mounted to move on said frame, means for producing a step-by-step motion of said carriage, a plurality of sets of type bars, each set comprising a series of types adapted to strike on the same printing point and the several sets being spaced from each other to write on separate points of the platen, members in each set for actuating said type bars, an electromagnet in each set adapted to operate the actuating member of either of the types of its associate set, a circuit comprising a source of current, means for selectively inserting in said circuit a number of said electromagnets, a part carrying said electromagnets, members adapted to be shifted in position preparatory to engage said part, said members being in number equal to that of the types of each set and each of them being adapted to stop said part with the electromagnets in front of the actuating members of the respective type bars in the several sets, means for moving said part and electromagnets towards said stops, a member locking said part and electromagnets against said moving means, means operated by said stopping members for releasing said locking member after one of the said stopping members has been carried in position to engage said part, electromagnets for shifting said stopping members these electromagnets being inserted in said circuit, 130
4. A typewriter comprising a frame, a platen carriage mounted to move on said frame, means for producing a step-by-step motion of said carriage, a plurality of sets of type bars, each set comprising a series of types adapted to strike on the same printing point and the several sets being

and key operated means for selectively energizing said stop shifting electromagnets and for energizing said type actuating electromagnets, and means for restoring the 5 parts in the normal position, these means being controlled by an electromagnet, and means for energizing this electromagnet after completing each actuation of a type bar.

10 6. A typewriter comprising a frame, a platen carriage mounted to move on said frame, means for producing a step by step motion of said carriage, a plurality of sets of type bars, each set comprising a series 15 of types adapted to strike on the same printing point and the several sets being spaced from each other to write on separate points of the platen, members in each set for actuating said type bars, an electromagnet for 20 each set adapted to operate the actuating

member of either of the types of its associate set, a circuit comprising a source of current, means for selectively inserting in said circuit a number of said electromagnets, means for disconnecting from said circuit all said electromagnets after completing a platen carriage stroke, a part carrying said electromagnets, means for shifting said part and electromagnets in front of the actuating member of any selected type in the several sets, key operated means for closing the circuits of said electromagnets and means for restoring said part and electromagnets in their normal position after completing the impression of the selected 30 type.

Signed at Milan, Italy, this 12th day of November A. D. 1921.

RAFFAELLO LA PEGNA.
